TELEPHONE SYSTEM

Bernard Anthony Hensler and Charles Leonard Peters, London, England, assignors to Siemens Brothers & Company Limited, London, England

Application August 23, 1935, Serial No. 37,484
In Great Britain August 29, 1934

7 Claims. (Cl. 179—27)

This invention relates to telephone systems and more particularly to an arrangement suitable for use in a toll or trunk telephone system wherein each incoming call causes a switching apparatus 5 to set itself to a position indicative of the order of arrival of the call with respect to other calls, the several switching apparatus so set being released in the order of arrival of the respective calls and are thereupon caused to search for a 10 free subsequent circuit as these are rendered available. The setting and release of the switching apparatus may be controlled by a chain of relays which are operated and released respectively to control such operations, and the system 15 may be applied to a toll or trunk system wherein calls are set up on demand by operators, i. e. a "demand system".

A system of this type has already been suggested in which a distributor switch on being set 20 in motion by an incoming call searches for and tests into an outlet to a display panel and if other calls are awaiting attention the call is added to a queue, the switches stepping on and so moving the call to the head of the queue as 25 earlier display positions become available. If there are no other calls waiting in a queue and a subsequent circuit is available the distributing switch nevertheless tests into the first display position and is immediately released to search 30 for the subsequent circuit.

In the present invention improved call queueing arrangements are provided by arranging that in moving a call up the queue the distributing switches do not step but a common switching 35 mechanism associated with the display effects the moving up process by providing for the release of the switches in the display positions in turn as subsequent circuits become available. This arrangement is especially advantageous 40 where the distributing switches are high speed motor driven switches as the step by step action in the queue is avoided. A further advantage is gained by placing the display positions at the 45 end of the distributing switch bank so that if a subsequent circuit is available at a time when there are no calls in the queue a searching distributing switch is not stopped momentarily in a display position but proceeds directly to the outlet to the subsequent circuit.

50 It is, accordingly one feature of the present invention that switching apparatus taken into use by an incoming call is caused to search for a free subsequent circuit, such as a connecting circuit on an operator's position and if this search 55 is unsuccessful to assume a position correspond-

ing to the order of the call with respect to other calls which have failed to be connected to subsequent circuits. The several switching apparatus are released from such positions in the order of arrival of the calls as subsequent circuits are 5 rendered available to search for these circuits.

According to another feature of the invention switching apparatus taken into use by incoming calls and formed into a queue remains in the same position during the movement of the call to the 10 head of the queue until it is released to search for a subsequent circuit for the extension of the call.

The arrangements on which the incoming calls are thus "queued" may consist of a number of 15 relays which are operated seriatim as the calls take a position in the "queue", and arrangements may be provided whereby the relays are picked up in a continuous order of rotation irrespective of the actual relative position of a call in a queue. 20

In the application of the invention to a normal or semi-automatic system arrangements are provided for giving relief to the demand operators, by signalling a further operator or operators when more than a certain number of calls 25 are "queued" up. The further operator or operators may normally deal with other types of incoming calls.

In order to effect a certain economy modifications to the system of the prior invention may be 30 made whereby incoming lines are connectable to the switching apparatus already referred to over a searching switch, the switching apparatus having full availability to the subsequent connecting circuits.

One method of carrying out the invention is described by way of example in the following description of the arrangements illustrated in the accompanying drawings, wherein the invention is illustrated as applied to a toll or trunk 40 telephone system in which under normal traffic conditions calls are dealt with in the demand basis. It is to be understood that the invention is not confined on its application to such systems, but is capable of utilization in any system of call 45 distribution.

In Fig. 1 of the drawings are illustrated an incoming line circuit ILC, and a call distributor circuit DD. There is also illustrated a portion of an operator's cordless connecting circuit CC, 50 of which there is provided a number on each position, and a portion of an operator's position circuit OPC, only those circuit elements of these latter circuits necessary to the understanding of the present invention being shown.

In Fig. 2 is illustrated a lamp display circuit LDC, calling lamps DOP on a demand position and calling lamps OOP "demand" and "incoming" on a further or omnibus position. A further portion of an operator's position circuit OPC is shown in this figure.

An incoming line circuit ICL Fig. 1 includes a step by step switch or uniselector P having wipers and arcs p_1 to p_5 , driving magnet PDM, and interrupter contacts pdm . The line relay is designated LA, the test relay TA and a switching relay H. The incoming line, junction or trunk is designated JCT. The arcs p_2 and p_3 are concerned with the connection of the speaking wires, the arc p_1 with the testing circuit, the arc p_4 for determining the type of call, i. e. whether it is an ordinary call or one from a coin box. The arc p_5 is a homing arc.

The distributor circuit includes a motor driven switch or uniselector D with wipers and arcs 1 , $1a$, $\dots$, 4 , $4a$, and a latch magnet LM. The circuit for and the driving motor of the switch being well known per se is not shown.

Each arc of contacts consists of two rows of 52 contacts each, a double-ended wiper being adapted to traverse the rows in succession. The arcs are associated in pairs, namely, 1 and $1a$, 2 and $2a$, and so on, and it is arranged that during search when the wipers of an arc have traversed the contacts in both rows of the arc a switching relay WS is operated to connect the main circuit wire to the wiper of the other arc of the pair. The arcs 1 , and $1a$, and 2 , and $2a$, are for connecting through the positive and negative wires, and the arcs 3 , and $3a$, and 4 , and $4a$, are concerned with testing into the connecting circuits.

The connecting circuits at the several operators' positions are connected to the contacts on the several arcs. To the final eleven contacts in the second set of contacts of arc $4a$ are connected the wires Id , and OF which lead to the lamp display circuit Fig. 2. Connections are also made from certain of the ten contacts in arcs $3a$ and $2a$ corresponding to the contacts of arc $4a$ to which the wires Id are connected, the purpose of these connections being explained fully hereinafter. The connecting circuits are commoned over the arcs of the distributor switches of the several distributor circuits, the connecting circuits including those on demand positions, omnibus and other relief positions. There is provided a line relay L, a releasing relay B, a testing relay T, and switching relief relays S and SS respectively. The relay TCO is provided for determining the origin of a call, e. g. whether it has been originated over an ordinary line or a call box line. The relay RR is a ringing relay for applying a ringing current back to a calling party. The functions of relay DS will be best understood from the subsequent detailed description, but generally they are to modify the testing circuit for testing in to the connecting circuits after a call has been released from association with the lamp display circuit.

The portion of the connecting circuit illustrated in Fig. 1 shows contacts SPK 1 , SPK 2 and SPK 3 of a speaking key and relays SK, SL, BA, and AS this being the order in which the relays are operated. The functions of the relays will be best understood from the following detailed description. The elements of the operator's circuit OPC Figs. 1 and 2 include contacts CA 1 and CA 2 of a call answering key, and contacts RA (Fig. 1) of a release answering key. The func-

tions of the relays CG, CN, and MN will be described in detail hereinafter.

The lamp display circuit Fig. 2 includes step by step switches or uniselectors AB and BA. The arcs $ab_1 \dots ab_8$ of switch AB are shown, but only the arc ba_1 of switch BA is shown, the other arcs of the switch BA being associated with the lamp multiple extending over the arcs $ab_6 \dots ab_8$ and the method of connection of the multiple to the arcs will be readily understood from the consideration of the wiring of arcs $ab_6 \dots ab_8$. The multiple wiring from the arcs $ab_6 \dots ab_8$ extends to the display lamps 1-10 on the demand operators' positions DOP, and it will be seen that the multiple wires over the arcs are slipped at each arc so that the first contact of the arc ab_6 is connected to the wire leading to display lamp 1, the first contact in the arc ab_7 is connected to the wire leading to display lamp 2 whilst the multiple wire to lamp 1 appears at the second contact in the arc and so on over the remaining arcs. The "demand" lamps on the omnibus position OOP are connected in parallel with the lamps on the demand position DOP.

The arc ab_1 is concerned with the stepping and homing of the switch AB, and the object of the arcs ab_2 and ba_1 is to ensure that the switches AB and BA are always in alignment, the relay SY controlling the stepping of the switch BA to bring it into alignment with switch AB.

The wires $Id_1 \dots Id_{10}$ from the arc $4a$ of the distributor switch are connected seriatim to the relays A-J, contacts of the relays A-J being connected seriatim to the wipers of arcs $ab_6 \dots ab_8$.

The functions of the various relays shown will be best understood from the subsequent detailed description.

An omnibus position normally deals with incoming calls signalled on the "incoming" lamps quite independently of the traffic on the demand operator's position unless excessive congestion exists on the latter, whereupon the "incoming" lamps on a particular omnibus position or positions are disconnected and the "demand" lamps connected up by the operation of relay AA. Such a condition is indicated to a supervisory operator over the lead SP.

The general operations of the arrangements illustrated are as follows: Upon a call being made over a junction or line JCT the switch P in ILC searches for and tests into a free distributor circuit DD.

Normally one or more demand operators will have a position connecting circuit assigned which is brought about by throwing the speaking key SPK associated with the connecting circuit and the call answering key CA in the position circuit. On the seizing of a distributor circuit DD the switch D is caused to hunt for an assigned connecting circuit, and when such is found the calling party is switched through to the operator who then sets up the desired connection.

If the call had originated at a call box or over a line demanding special treatment, the operator would receive a tone on the origination and switching through of the call, and then cause the conversational connection to be set up by throwing a key (not shown) in the connecting circuit which applies earth to the negative wire.

The operator controls the release of the call and can release it by throwing either the key REL in the connecting circuit CC or the key RA in the position circuit OPC.

In the event of a call being made whilst a con-

necting circuit is not assigned, the distributor switch hunts until a free circuit over one of the display leads *ld* is found and tests into this to cause a calling lamp to light, and busies the circuit against other searching distributor switches which will test into the other display circuit leads. The calls are thus caused to be queued up in the order of origination, and when the display circuit is full, i. e. ten calls are stored, other searching distributor switches test into an overflow circuit over the lead *OF* to which the call meter *CM* is connected at this time to indicate the number of calls so held.

An operator causes the release of the call from the head of the queue by simply assigning a connecting circuit, the distributor switch associated with this call then being released from the display to search for the assigned connecting circuit whereupon the switches *AB* and *BA* step to move up, in effect, the remaining calls in the queue one in the order of their priority of calling. Calls held on the overflow circuit are released and one of these tests into the lamp circuit just freed which now is so connected as to place the call at the lowest position in the queue, whilst the other calls are again connected to the overflow circuit.

If a call is held in the display circuit for more than a predetermined period a timing circuit comes into operation to cause calling lamps to light on a relief position (over the lead *AL* Fig. 2) so that a relief operator is signalled. Similarly, in the example described, a relief operator is signalled if the number of calls in the queue reaches seven, the relief operator being held until the number falls below six. If the number of calls in the queue reaches nine then the "incoming" lamps associated with a particular omnibus operator's position are disconnected, and the "demand" lamps are connected in parallel with the lamps on the demand operator's position so that the omnibus operator can assist the demand operator. The omnibus position is disconnected when the number of calls in the queue falls below eight.

The circuit arrangements illustrated will now be described in detail.

Assuming that a call is made over an ordinary line, i. e. a line from an ordinary local subscriber or over a local selector, then a loop will be applied to the positive and negative wires *JCT* resulting in the operation of relay *LA* over contacts *h4* and *h5*. At contacts *la1* earth is applied to the *P* wire to busy the line at preceding selectors, if the call has been made over a selector, and at contacts *la3* the test relay *TA* is connected to the wiper of the test arc *p1*. A circuit is closed from earth over contacts *ta1*, *h3*, *la2*, *pdm* to magnet *PDM* to battery and magnet *PDM* energizes and opens the contacts *pdm* whereby the above circuit is broken and the magnet de-energized and the wipers of the switch are stepped on to the first outlet in their arcs.

If the outlet is busy the relevant contact in arc *p1* will be marked busy by an earth applied from the distributor circuit *DD* and as a consequence relay *TA* will be short circuited and prevented from operating and therefore when the contacts *pdm* close on the de-energization of the magnet *PDM* the circuit for the magnet is again closed and the wipers stepped on to the next outlet in the manner before described.

A free outlet will be marked by a battery potential over contacts *on2*, *ss6* and *b1* in the distributor circuit *DD* and as a consequence when

the wiper *p1* meets a free outlet relay *TA* operates from the battery potential over arc *p1*, and contacts *la3*. The driving circuit for the magnet *PDM* is opened and an obvious circuit is closed for the right hand coil of relay *H* at contacts *ta1*. Relay *H* operates and at contacts *h1* locks itself temporarily over its left hand coil to earth over contacts *la1*, and at contacts *h2* prepares a point in a locking and busying circuit over which it locks on the release of relay *LA*. 10

At contacts *h3* a further point in the driving circuit for magnet *PDM* is opened. Contacts *h6* prepare a circuit for the operation of relay *TCO* over its coil (I) and arcs *p5* and *p4*, but however as the line calling is an ordinary line no connection is made to the contact in arc *p4*. 15

At contacts *h4* and *h5* relay *LA* is disconnected, relay *LA* being slow to release and does not release immediately and the incoming loop is extended to relay *L* in *DD* over contacts *rr1* and *rr2* and relay *L* operates. A circuit is closed for relay *B* from earth over contacts *ss5* and *ll* and relay *B* operates. Contacts *l2* prepare a holding circuit for relays *SS* and *DS*, and, contacts *l3* prepare a holding circuit over the arc *p1* for holding the circuit *ILC*. Contacts *l4* prepare a supervisory circuit for the supervision of the call.

Upon the operation of relay *B* an earth is applied over contacts *b1* and arc *p1* to short circuit relay *TA*, hold relay *H*, and busy the outlet at the preceding selector if such has been employed. Relay *LA* releases shortly after relay *B* operates and disconnects relay *TA*. Contacts *b2* connect a ringing signal tone from lead *RS* and over contacts *ss7* to the positive wire and thence to the calling party. Contacts *b3* close a point in the circuit for the test relay *T*. 30

A circuit is closed from earth over contacts *t1*, *s1*, *tc6*, *b4*, latch magnet *LM* to battery and earth, and the latch magnet operates closing contacts whereby the circuit of a driving motor is closed, the motor in rotating driving the wipers of the distributor switch in known manner. 40

Under normal operating conditions, i. e. when calls can be answered on demand, a connecting circuit, a portion of which is shown in the rectangle *CC*, will be assigned on one or more operators' positions, the assignment of a connecting circuit necessitating the throwing of a speaking key *SPK* associated with the connecting circuit *CC* and the connect answer key *CA* in the operator's circuit *OPC*. On the closing of the contacts *SPK2* a circuit is closed from battery over a resistance in the operator's position circuit *OPC*, 50 the coils of relay *SK* in series over the contacts *SPK2*, contacts *s11* to earth and relay *SK* operates and at its contacts *s11* short circuits its left hand coil. A circuit is closed from earth over the left hand coil of relay *MN* in *OPC*, contacts *ba1*, *SPK3*, *sk2*, relay *SL* to battery and earth and relays *MN* and *SL* operate in series. Contacts *s11* hold relay *SK* over its right hand coil independently of contacts *SPK2*. A battery potential is applied to the contact in the arc *4* or *4a* of the distributor *D* corresponding to the connecting circuit, over relay *BA*, key contacts *REL*, contacts *s13*, *sk4*, key contacts *RA* and *CA1* in *OPC*, and contacts *s12*. 55

Assuming that an assigned connecting circuit exists in the arcs *1*, *2*, *3*, *4* of the distributor switch *D* then the wipers of the switch are driven until the wiper of arc *4* meets the contact marked by battery over the relay *BA*, whereupon a circuit is closed from earth contact *en1*, (also shown in 70

75

Fig. 2) contacts *ba3*, arc and wiper *3*, contacts *ws4*, *ss4*, *ds3*, *b3*, rectifier *r*, both coils of relay *T* in series, contacts *ws5* to the marked contacts and relay *T* operates and at contacts *t1* opens the circuit for the latch magnet *LM*, whereby the wipers of the switch *D* are brought to rest, short circuits the upper coil of relay *T*, and relays *T* and *BA* operate in series. The lower coil of relay *T* is of low resistance and the earth over it busies the outlet to the connecting circuit against other searching distributors by preventing their *T* relays from operating. At contacts *ba2* relay *BA* locks itself independently of contacts *sl2* and *CA1*, and at contacts *ba1* disconnects the left hand coil of relay *MN* and connects in its place the right hand coil of this relay in series with relay *CG*. Relays *SL* and *MN* hold and relay *CG* operates. At contacts *ba3* a circuit is prepared for relay *AS* but this relay cannot operate in series with the upper coil of relay *T* owing to the disposition of the rectifier *r*. Contacts *ba4* close the circuit of the supervisory lamp *ASL* in front of the operator.

When relay *T* operates and contacts *t1* change over, a short circuit is removed from relay *S*, and this relay operates in series with the latch magnet *LM*, the latch magnet however not being energized sufficiently in this series circuit to withdraw the latch.

Relay *S* at contacts *s1* locks itself independently of the latch magnet and at contacts *s2* and *s3* prepares to extend the positive and negative conductors to the connecting circuit *CC*. Contacts *s4* prepare a point in a circuit for relay *AS* in *CC*. Contacts *s6* do not concern us at present.

A circuit is closed from earth over the off normal contacts *on1*, which as the switch is off normal are closed, contacts *s5*, coil (I) of relay *DS*, relay *SS*, resistance to battery and earth, and relays *SS* and *DS* operate.

At contacts *ss1* and over contacts *l2* a locking circuit is closed for relays *SS* and *DS* independently of the contacts *on1* and *s5*. Contacts *ss2* and *ss3* prepare further points in the positive and negative wires to the connecting circuit *CC*.

Contacts *ss4* connect earth over *l4* and *s4*, and over *ws4*, *ba3*, relay *AS* to battery and relay *AS* operates to disconnect and extinguish the supervisory lamp *ASL* at contacts *as2*. A locking circuit is closed for relay *AS* over contacts *as1* and *SPK1* to prevent relay *AS* being released whilst the speak key is operated. At contacts *ss5* an obvious circuit is closed for relay *TCO* and the circuit for relay *B* is opened. Contacts *ss6* perform no function at this stage. Relay *TCO* operates.

When relay *B* releases after its slow releasing period the circuit *ILC*, and the preceding selector if such has been used, are held over contacts *b1*, *ss6*, and *s6* and *l3* in parallel.

On the operation of relay *TCO* contacts *tco2* and *tco3* complete the connection of the positive and negative wires to the connecting circuit. The other contacts of relay *TCO* will be referred to hereinafter.

The operator may now converse with the calling party and completes the connection to the wanted party. The speak key *SPK* in *CC* and the key *CA* in *OPC* are restored and relays *CG*, *MN*, and *SL* are released at *SPK3*. Relay *SK* is released at contacts *sl1*, and relays *BA* and *T* are held over the contacts *ba2* and *sl3*.

When the calling party clears the line, or flashes the operator to call her attention, relay *L* releases and at contacts *l4* opens the circuit for

relay *AS* in *CC*, the relay releasing to light the supervisory lamp *ASL* in front of the operator at contacts *as2*.

The operator may release the distributor circuit by operating the release key *RA* in *OPC* or *REL* in *CC* and thereby release relay *T* which at contacts *t1* short circuits relay *S*.

On the release of relays *L* and *S* the earth is removed from the private wire to the circuit *ILC*, and the preceding selector, and relay *H* is released which at contacts *h6* closes an obvious homing circuit for the switch *P*.

At contacts *s5* the original circuit for relays *SS* and *DS(I)* is opened, but these relays remain held over *on1*, *l2*, and *ss1*, and a homing circuit for the switch *D* is closed over *on1*, *s5*, *b4*, *LM* to battery and the switch commences to home and when the home position is reached contacts *on1* open disconnecting the circuits for the magnet *LM* and relays *SS* and *DS*. Relays *SS* and *DS* release, and relay *SS* releases relay *TCO*. The testing circuit for the switch *P* is held open at contacts *on2* until the switch reaches home. The circuits are now at normal in preparation for dealing with further calls.

If the circuit *ILC* terminates a call box line the connection from the arc *p4* to the coil (I) of relay *TCO* over contacts *tco4* will be completed, and it will be seen that on the operation of relay *SS* relay *TCO* will be prevented from operating over this coil as it is short circuited. As a consequence a tone will be given to the operator over contacts *tco2* and the positive conductor and the operator on observing such tone throws a key (not shown) in the connecting circuit whereby an earth is applied to the negative wire and relay *TCO* is operated over its coil (II) and contacts *tco3*, *ss3*, and *s3*.

Relay *TCO* operates and performs the functions before described.

In the event of the assigned connecting circuit being connected to the arcs *1a*, *2a*, *3a* and *4a* of the switch *D*, then when the wipers meet the last contacts in their arcs a circuit is completed from earth last contact in arc *3*, contacts *ws4*, *ss4*, *ds3*, *b3*, rectifier *r*, relay *T*, *ws5*, last contact in arc *4*, (coil (I) of relay *WS* to battery and relays *T* and *WS* operate. At contacts *ws1* relay *WS* locks itself over its coil (II) to contacts *on1*. At contacts *ws2*—*ws5* the arcs *1*, *2*, *3*, and *4* are disconnected and arcs *1a*, *2a*, *3a*, and *4a* are connected up. Contacts *ws6* prepare to lock relay *TCO* over its coil (I). The circuit of relay *T* is opened when contacts *ws5* change over and relay *T* releases. Relay *T* is operated only for a very short time which may be insufficient to allow relay *S* to operate. Even so, if relay *S* does operate relay *SS* and *DS* cannot operate as they are short circuited at this time by the connection of earth over contacts *ss2*, *s2*, *ws2* and arc *1a*, the earth to the other side of the relays being derived over contacts *on1* and *s5*.

The switch now searches over the second half of its arcs for the assigned connecting circuit and when this is found the operations as before described take place.

If it is required to ring a calling subscriber who has left the line the operator throws a ringing key (not shown) in the connecting circuit whereby a battery potential is applied to the positive wire which operates relay *RR*. At contacts *rr1* and *rr2* ringing current over the leads *R* and *RRS* is applied to the calling line.

In the event of a connecting circuit not being assigned such as will happen at busy periods the

distributor switch D drives until the wiper of arc 4a meets the wires ld leading to the lamp display circuit Fig. 2. Assuming that the display is entirely free then when the wipers of arc 4a meets the contact connected to the lead ld a circuit is closed from earth over contacts tco1, arc 3a, contacts ws4, ss4, ds3, b3, rectifier r, relay T, contacts ws5, arc 4a, lead ld1, relay A (Fig. 2), arc ab3, contacts co1, st3, arc ab4, resistance to battery and relays T and A operate. Relay T on operation allows S to operate at contacts t1 and locks itself in series with relay A independently of contacts tco1. Relay SS and coil (I) of relay DS are short circuited over contacts ss2, s2, ws2 and arc 1a so that they cannot operate.

A circuit is closed from earth over contacts ss3, s3, ws3, arc 2a, coil (II) of relay TCO to battery and relay TCO operates and locks over contacts ws1 and tco1. At contacts tco5 a circuit is closed for relay DS over its coil (II) and contacts ss5 and relay DS operates. Relay B is held independently of contacts t1 at contacts ds2 so that relay B cannot be released in the event of the calling party leaving the line.

When relay A, Fig. 2, operates it closes a locking circuit for itself at contacts a1 independently of the arcs ab3 and ab4, and at contacts a2 prepares a circuit for relay B. Contacts a3 prepare a point in the circuit to the overflow lead OF, but this circuit is not completed until a maximum number of calls are stored on the display. Contacts a4 and a5 close in parallel and complete a circuit over arc ab6 for the calling lamp 1 on the demand operator's position DOP. Relay AC operates in parallel with lamp 1 and over contacts st6 and locks over contacts ac1 independently of the former contacts. Contacts ac2 prepare to connect an earth to the wire ld leading to the distributor circuit DD to release the relay T thereof when the call is released from the display. Contacts ac3 prepare an energizing circuit for the magnet BADM, and contacts ac4 prepare an energizing circuit for the magnet ABDM. Contacts ac5 prepare a circuit for the upper coil of relay ST and contacts ac6 prepare a circuit for the lower coil of this relay. Relay EN also operates over its left hand coil in parallel with lamp 1. At contacts en2 a further point is prepared in the circuit for relay ST. At contacts en1 (see CC Fig. 1) the earth for the normal testing operations of the relays T in the distributors is removed from all connecting circuits associated with the distributor switches so that distributors searching for a connecting circuit in response to fresh calls are prevented from testing in whilst calls are waiting on the display lamps.

The distributor switches D and their associated circuits over which succeeding calls are made are caused to test into and associate themselves with the relays B—J which operate in succession as calls arrive and at their respective contacts 4 and 5 close the circuits for the lamps DOP2—O over the arcs ab7—ab8 and similar arcs of the switch BA, that is, provided meanwhile no calls have been answered. When the maximum number of calls are queued up on the display lamps, and therefore relay J operated, further searching switches test into the lead OF which extends to the call meter CM over contacts j3 and arc ab5, the call meter indicating the number of calls so connected. The resistance in the connection from each distributor circuit to the lead OF is individual to the distributor circuit so that the relays T of other searching distributors are not affected and can freely test into the lead OF.

It will be seen that providing the switches AB and BA are standing in corresponding positions a circuit is closed over arcs ab2 and ba1 for relay SY which at contacts sy1 opens the self drive circuit for the magnet BADM.

Upon an operator assigning a connecting circuit by throwing the speaking key SPK associated with the connecting circuit and by throwing the connect answer key CA in the position circuit OPC, a circuit is completed from earth over contacts CA2, relay CN, contacts cg1, mn1, (relay MN being operated at this time in series with relay SL Fig. 1), en2, ac6, st1, lower coil of relay ST to battery and relay ST operates and locks itself over its upper coil and contacts st2, 15 and ac5. When contacts st1 are in the mid position relay CN which is a very fast operating relay operates in series with the resistance and closes a circuit in series with itself for coil (II) of relay CG over contacts cn1 but this coil is shunted for 20 the moment. Relay CG operates when contacts st1 change over and at contacts cg1 opens a point in the operating circuit for the lower coil of relay ST.

A further point in the operating circuit for the 25 lower coil of relay ST is opened at contacts st1 and this coil, being shunted, gives the relay slow releasing characteristics.

Thus the signal transmitted from the operator's circuit OPC to the relay ST is of very short duration and occupies only a part of the movement of the contacts st1, this minimizing the chances of the simultaneous connection of two operators' positions to the display circuit.

A circuit is closed from earth over contacts 35 sy1, ac3, st4, magnet BADM to negative and the magnet energizes. A circuit is also closed from earth over contacts ac4, st5, arc ab1, magnet ABDM to battery and this magnet energizes. At contacts st6 a point in the original operating circuit for relay AC is opened, but this relay holds over contacts ac1.

An earth is extended over contacts ac2, st3, co1, arc ab3, to relay A short circuiting this relay and also relay T in the distributor circuit both of 45 which relays release.

Upon the relapse of relay T in the distributor circuit relay S is short circuited at contacts t1 and relay S releases. A circuit is thereupon closed from earth over contacts on1, s5, tco6, b4, 50 magnet LM to battery and the magnet energizes to close the circuit of the driving motor and the wipers of the switch are advanced to the home position where the contacts on1 open releasing relay WS which in turn releases relay TCO at contacts ws6. Upon the relapse of relay TCO the circuit for the magnet LM is completed over contacts t1, s1, tco6 and b4 and the wipers are driven in search of the assigned connecting circuit, and when this is found relay T operates 60 from earth over contacts tco1, ds3, b3, rectifier R, relay T, contacts ws5 and over arc 4 or 4a. Relay T on operation allows relay S to operate and the operations as before described take place.

When relay A in the lamp display circuit Fig. 2 releases the circuit for the lamp DOP1 and for relay AC is opened at contacts a4 and a5, and relay AC releases. At contacts ac3 and ac4 the circuits for the magnets BADM and ABDM are 70 opened and the wipers of the switches BA and AB are stepped. The short circuit is removed from relay A at contacts ac2. The holding circuit for the upper coil of relay ST is opened at contacts ac5 but relay ST does not release im- 75

mediately as it is rendered slow to release by virtue of its shunted lower coil so that the circuit to the operator's circuit is maintained open at contacts *st1* for a short period to enable the apparatus in the display circuit to function correctly.

- As the call of the first order of priority has been answered it is necessary that the other calls that are queued up on the display lamps should all be moved up one in their order of priority. This is accomplished over the arcs *ab6*, *ab1* etc. It will be seen that when the switch AB steps a circuit is closed over contacts *b4* and *b5*, second contact of arc *ab1* to lamp *DOP1* and to relay 10 *AC* in parallel therewith when relay *ST* releases. Thus the call of the second order of priority is moved into the first place, whilst the third call lighting the lamp *DOP3* is moved into second place and associated with the lamp *DOP2* and so on. 15

When the switch AB steps the circuit to the lead *OF* is broken at arc *ab5* and the wipers are stepped on to the contacts connected to the contacts *a3*. Thus all of the T relays in the distributors held over the lead *OF* are released and the associated switches search for the free display lamp circuits, one of the distributors seizing the circuit of the freed relay A whilst the unsuccessful switches continue in operation until they again test into the lead *OF* over contacts *a3*, arc *ab5*, and the call meter *CM*. 20

When the operator has dealt with the call the key *CA* is restored releasing relays *CN* and *CG* and that portion of the position circuit shown in Fig. 2 is restored to normal.

It will be seen that under normal operating conditions when no calls exist on the calling lamps, and relay *EN* is normal, relay *CO* is operated on the operation of the key *CA* and at contacts *co1* opens a point in the test circuit into the display circuit. 25

When seven calls exist on the calling lamps *DOP* a circuit is closed for relay *ON* over its right hand coil in parallel with the lamp *7* and relay *ON* operates and locks over its left hand coil in parallel with lamp *6*. An earth is connected over contacts *oom2*, *on2*, to the lead *AL* leading to the lamp display circuits on one or more relief or omnibus positions whereby the operators on these positions are signalled to assist in the answering of the calls. Relay *ON* is released when the number of calls falls below six. 30

In the event of nine calls becoming queued up a circuit is closed for the right hand coil of relay *OM* in parallel with the calling lamp *9* and relay *OM* operates and closes at contact *om1* a circuit for its left hand coil in parallel with lamp *8*. 35

At contacts *om2* a circuit is closed for relay *AA* at one or more further relief or omnibus positions, the operating earth being derived over contacts *oom2* which are contacts of a relay similar to relay *OM* but which is associated with the display lamps on an omnibus position, so that if more than a certain number of incoming calls are signalled in this position the omnibus positions cannot be called to assist in handling the traffic on the demand position. 40

Relay *AA* operates and at contacts *aa1* to *aa10* connects the demand display lamps on the omnibus position *OOP* in parallel with the display lamps on the demand position so that the corresponding lamps light. The circuits for the incoming lamps on the omnibus position are dis- 45

connected at contacts *aa11* to *aa20*. Thus an omnibus operator is called to assist the demand operators and may answer the calls in an exactly similar manner to that previously described, the omnibus operator having connecting circuits associated with the demand distributor circuits. 5

At contacts *ac21* a circuit is closed over the wire *SP* for a supervisory device to indicate the state of congestion to a supervisory operator. When the number of queued calls fall below eight relay *OM* is released releasing relay *AA*, and the demand calling lamps on the omnibus position are disconnected and the incoming lamps re-connected. 10

If however nine or more incoming calls are queued up on the incoming calling lamp display on the omnibus position a relay, say *OOM* similar to relay *OM* in *LDC* associated with that display will be operated and contacts *oom2* will be open. Thus it will not be possible to interrupt the incoming traffic to the omnibus operator's position until some of the incoming traffic has been dealt with. 15

In order that calls are not held beyond a certain period during the time that insufficient calls are in the queue to signal the omnibus position there is associated with each of the relays *A*—*J* of the lamp display circuit *LDC* two relays, such as relays *SA* and *ZA*, only those relays associated with the relay *A* however being shown, the other pairs being connected and operated in an identical manner. 20

Two contacts *a6* and *a7* control the operation of the relays *SA* and *ZA*, and as all of the other relays *B*—*J* are provided with similar contacts, which however are not shown, the relays are designated as having seven contacts. 25

Earthed impulses are periodically and alternately delivered over the leads *S* and *Z*.

Assuming that a call is held on relay *A* over a period during which the impulses are delivered to the leads *S* and *Z*, then, when the impulse is given over the lead *S* a circuit is closed for the right hand coil of relay *SA* over contacts *za2* and *a6*, and relay *SA* operates, and locks over its left hand coil, contacts *a1*, left hand coil of relay *ZA*, and contacts *sa1*. Relay *ZA* will not operate in this circuit. When the impulse occurs over the lead *Z* relay *ZA* operates over its right hand coil and contacts *za2*. At contacts *za1* a locking circuit is closed for relay *ZA* over its left hand coil and the left hand coil of relay *SA* is short circuited making the relay slightly slow to release. The circuit for the right hand coil of relay *SA* is opened at contacts *za2* and after a short period relay *SA* releases. A circuit is closed for relay *DL* at contacts *za3*, and relay *DL* operates. 50

At contacts *dl1* a circuit is closed for relay *AA*, and at contacts *dl2* an earth is applied to the lead *AL* to operate similar relays such as *AA* on the relief positions. 55

The switches *AB* and *BA* are stepped in the manner described to alter the position of the calls in the queue until the switch *AB* is stepped to the twenty first contact whereupon a circuit is closed from earth over contacts *abdm*, arc and wiper *ab1* magnet *ABDM* to battery and the switch *AB* is stepped to its normal position under the control of its interrupter contacts. Immediately the wiper of arc *ab2* steps out of alignment with the wiper of arc *ba1* relay *SY* releases and at contacts *sy1* closes the circuit for magnet *BADM* and the switch *BA* homes whereupon relay *SY* operates and opens the homing circuit for magnet *BADM* at contacts *sy1*. 60

The common relays NA in the lamp display circuits are night alarm relays adapted to operate when any lamp is alight to operate an alarm.

We claim:

5. 1. In a telephone system, a group of connective circuits, a group of hunting switches of the homing type having access to said circuits as first choice, a group of overflow circuits accessible to said switches as second choice, whereby 10 switches operated at times when no connective circuits are available will connect with successive overflow circuits, and controlling means operating on switches connected with overflow circuits in the order in which the connections are established for releasing a connected switch and for 15 causing it to rehunt over said connective circuits each time a connective circuit becomes idle.

2. In a telephone system, a group of individual overflow circuits, automatic switches having access to said circuits if no regular outlets are 20 available, means for making each individual overflow circuit busy when seized, a common overflow circuit which is not made busy when seized and which may therefore be occupied by a number of 25 switches when the individual overflow circuits are all busy, means for successively releasing the switches connected to individual overflow circuits, and means effective whenever an individual overflow circuit is freed for causing the switches 30 connected to the common overflow circuit to hunt for the free individual overflow circuit.

3. In a telephone system, a group of automatic switches, a group of connective circuits accessible to said switches, a group of individual overflow 35 circuits accessible to said switches only if none of said connective circuits are available, a common overflow circuit accessible to said switches only if all said individual overflow circuits are busy, means operative at a time when one or more 40 switches are connected to the common overflow circuit and responsive to a connective circuit becoming available for releasing one switch connected to an individual overflow circuit and for 45 causing it to hunt for the available connective circuit, and means for releasing all switches connected to said common overflow circuit and for causing them to hunt for the free individual overflow circuit.

4. In a telephone system, a group of overflow 50 circuits, a corresponding group of lamps, switches

having access to said circuits, means for busying each circuit when seized and for lighting the corresponding lamp, means for releasing switches from overflow circuits one at a time, and means intervening between the said circuits and lamps and operative every time a switch is released for changing the relation between said circuits and said lamps to associate each circuit with a different lamp.

5. In a telephone system, a group of relays 10 numbered consecutively, a group of lamps correspondingly numbered, means for energizing said relays in the order of their numbering to light the corresponding lamps, means for releasing said relays in the same order, and means operative each time a relay is released for shifting each relay into association with the next lower numbered lamp.

6. In a telephone system, a plurality of connective circuits common to a plurality of operators, automatic switches having access to said circuits, circuit arrangements such that the connective circuits are normally unselectable by said switches and are individually made available for selection when the operator handling the calls 20 is ready to take a call, overflow circuits accessible to said switches at times when no connective circuits are available for selection, and means responsive to a predetermined number of overflow 25 circuits becoming occupied for automatically signalling another one of said operators to assist in handling the calls.

7. In a telephone system, a plurality of connective circuits common to a plurality of operators, automatic switches having access to said circuits, circuit arrangements such that the connective circuits are normally unselectable by said switches and are individually made available for selection when the operator handling the calls is 30 ready to take a call, overflow circuits accessible 35 to said switches at times when no connective circuits are available for selection, means for successively releasing switches from overflow circuits to permit them to hunt for connective circuits as the latter are made available by the operator, and means for automatically signalling another operator if a switch remains connected 40 to an overflow circuit for a predetermined time.
